EDUCATIONAL TOY FIGURE

William B. Moody, 627 Terrell Mill Road, College Park,
Ga. 30377, and Dorothy B. Whitney, 2060 Sylvania
Ave., Decatur, Ga. 30467

Filed Feb. 12, 1969, Ser. No. 15,749

Term of patent 7 years

Int. Cl. D21—02

U.S. Cl. D34—15

Fig. 1

Fig. 2

Fig. 3

Fig. 4

Fig. 5

Fig. 6

FIGURE 1 is a side elevational view of an educational toy figure showing our new design;

FIGURE 2 is a top plan view thereof;

FIGURE 3 is a bottom plan view thereof;

FIGURE 4 is a side elevational view of the opposite side thereof from FIGURE 1;

FIGURE 5 is a front end view thereof taken from the right end of FIGURE 1; and

FIGURE 6 is a rear end view thereof taken from the left end of FIGURE 1.

We claim:

The ornamental design for an educational toy figure, as shown.
